DESIGN FOR A CREAM PITCHER OR SIMILAR ARTICLE

Paul C. Tietz, Melrose Park, Ill., assignor to The Richardson Company, Lockland, Ohio, a corporation of Ohio

Application July 31, 1933. Serial No. 48,888

Term of patent 3½ years

To all whom it may concern:

Be it known that I, PAUL C. TIETZ, a citizen of the United States, residing in Melrose Park, in the county of Cook, and State of Illinois, have invented a new, original, and ornamental Design for a Cream Pitcher or Similar Article, of which the following is a specification, reference being had to the accompanying drawing, forming part thereof.

In the drawing:

The figure is a perspective view of the cream pitcher showing my new design.

The design may be applied without substantial change to a cream pitcher, a tea pot, a cup, or a sugar bowl.

I claim:

The ornamental design for a cream pitcher or similar article as shown and described.

PAUL C. TIETZ.
